UNITED STATES PATENT OFFICE.

WILLIAM HALE DRIGGS AND VERNON C. TASKER, OF WASHINGTON, DISTRICT OF COLUMBIA; SAID TASKER ASSIGNOR TO THE DRIGGS-SEABURY GUN AND AMMUNITION COMPANY, OF NEW YORK, N. Y.

RECOIL-OPERATED GUN.

SPECIFICATION forming part of Letters Patent No. 625,326, dated May 23, 1899.

Application filed March 17, 1898. Serial No. 674,226. (No model.)

To all whom it may concern:

Be it known that we, WILLIAM HALE DRIGGS and VERNON C. TASKER, citizens of the United States, residing at Washington, 5 in the District of Columbia, have invented certain new and useful Improvements in Breech-Loading Ordnance; and we do hereby declare the following to be a full, clear, and exact description of the invention, such 10 as will enable others skilled in the art to which it appertains to make and use the same.

Our invention relates to improvements in rapid-fire guns; and it consists, principally, in improved breech mechanism and means 15 for operating the same, in means for operating the breech-block and extractor semi-automatically or through the energy stored up in a spring or on the recoil of the gun, and also in means for independently operating 20 the breech-block and extractor by hand, if desired, and also in other novel details of construction and combinations and arrangements of parts, that will be hereinafter described and claimed.

25 Reference is had to the accompanying drawings, in which the same parts are indicated by the same letters throughout the several views.

Figure 1 represents a side elevation of the 30 rear portion of the gun from the trunnions to the breech, the mount being shown in section and parts being broken away. Fig. 2 represents a plan view of the structure shown in Fig. 1. Fig. 3 represents a side elevation 35 of the opposite side of the breech of the gun from that shown in Fig. 1, parts being broken away. Fig. 4 represents a central vertical section through the recoil-cylinder and contiguous parts of the gun and mount. Fig. 5 40 represents a side elevation, partly in section, of the forward end of the sighting-arm, parts being broken away, and illustrates the manner of connecting the sighting-arm to the gun and shows details of the firing mechanism. Fig. 6 represents a detail view, partly in section, 45 along the line 4 6 of Fig. 7, of the rocking slide and other parts of the gun-mount, the gun itself being removed and parts being broken away. Fig. 7 represents a double sec-

tion, the right half of said figure being along 50 the line 7' 7' and the left side of the figure being along the line 7' 7' of Fig. 6, in both instances looking in the direction of the arrows. Fig. 8 represents a detail view along the line 8 8 of Fig. 7, but showing a modified form of 55 the balancing-supports for the trunnions of the rocking slide. Fig. 9 represents a section through the breech of the gun along the broken line 9 9 of Fig. 10 and looking in the direction of the arrows. Fig. 10 represents 60 a rear view of the breech of the gun, partly in section, along the broken line 10 10 of Fig. 9. Fig. 11 represents a section along the line 9 11 of Fig. 10 and looking to the left in the said figure, the breech-block, however, being 65 shown in the open position. Fig. 12 represents a similar view to that shown in Fig. 11, except that the breech-block is removed from the gun, and illustrates the location and operation of the extractors. Fig. 13 represents 70 a front view of the firing-pin, showing section through the adjacent parts of the breech-block along the line 13 13 of Fig. 11. Fig. 14 is a perspective view of the firing-shaft as detached from the gun. Fig. 15 75 represents a perspective view of the breech-block as detached from the gun. Fig. 16 represents a perspective view of the breech-operating shaft and the arms carried thereby. Fig. 17 represents a rear view of one of the 80 extractors detached from the gun. Fig. 18 represents a side elevation of one of the extractors as engaging a cartridge-case. Fig. 19 represents a plan view of one of the extractors. Fig. 20 represents a section on the line 85 20 20 of Fig. 9 and illustrates the action of the cam for automatically opening the breech-block on counter-recoil. Fig. 21 is a perspective view of the pivoted cam for automatically opening the breech-block on counter-re- 90 coil. Fig. 22 is a section on the line 22 22 of Fig. 10, looking to the left. Fig. 23 represents a section on the line 23 23 of Figs. 9 and 10 and looking down. Fig. 24 is a plan view of part of the sighting-arm and illustrates de- 95 tails of the firing mechanism, and Fig. 25 is a perspective view of the trigger and parts contiguous thereto as detached from the gun.

- A represents the body of the gun, which is screwed or otherwise secured into the band B, provided with dovetail guides b and with the U-shaped downwardly-projecting portion B'. 5 These guides b slide in guideways c in the rocking slide C, which rocking slide is provided with trunnions C', supported on the yoke F' of the mount F and inclosed by the usual cap-squares D.
- 10 In order to lessen the friction of the rocking slide on its trunnions, and also throw the center of suspension of the rocking slide at about the axis of the trunnions instead of at the base thereof; the trunnions are recessed, 15 as at c', (see Figs. 3, 7, and 8,) and the weight of the rocking slide, gun, and connected parts is suspended on the supporting-pins E, as shown in Figs. 3 and 7, or E', as shown in Fig. 8. These supporting-pins may be screwed in 20 and locked by the set-screw e², as shown in Figs. 3 and 7, the yoke F' being slotted, as at f', and the pin E being provided with holes e' for capstan-bars, whereby the pin E may be adjusted for wear either on the pin or on the 25 trunnions, and the weight of the gun or a large portion thereof may be supported on these pins, or instead of this mode of adjustment the mode of adjustment shown in Fig. 8 may be adopted, where the pin E' is recessed at e³.
- 30 to receive the spindle e⁴, passing through the cup-springs e⁵. These springs should be so adjusted as to take the entire weight or nearly the entire weight of the gun, and thus relieve the pressure on the base of the trunnions.
- 35 By arranging the spindle and cup-springs as shown in Fig. 8 the pin E' may be removed and the spindle, with the cup-springs, may be withdrawn from its recess for cleaning, repair, or other purposes, the gun and rocking 40 slide being of course first lifted from the mount. By this arrangement of central support for the trunnions the gun is supported on a line at right angles to or intersecting the axis of the bore, and thus the tendency of the 45 gun or rocking slide to roll back on its trunnion-seat and produce the error known as "jump" is in a large measure, if not wholly, avoided.
- It will be seen that the pins E or E', which 50 should be made of resilient material, preferably of chilled steel, will spring back when the gun is fired, causing the shock of recoil to be taken on the rear portion of the trunnion-seat, as is ordinarily the case.
- 55 By having the lower side of the trunnions provided with a recess c', as shown in Figs. 3, 7, and 8, the liability of dust, dirt, grease, snow, or other foreign matter to accumulate in the recess or about the trunnion-support 60 is obviated.

The rocking slide C projects to the rear, as shown at C², and has detachably secured thereto the sighting-arm C³, carrying the shoulder-piece C⁴, and the hand-grip C⁵, used 55 for steadyng the gun on the target. The front end of the rocking slide is provided with a U-shaped downward projection C⁶, closed

in front and perforated at c¹⁵, with the socket c¹¹ in front of the perforation c¹⁶. In through this perforation c¹⁵ the piston-rod H of the recoil-cylinder G passes, which piston-rod is held in place by a nut H', having a spherical base h' engaging in the socket c¹¹, and thus allowing sufficient freedom of motion of the piston-rod H about its front bearing. This 75 piston-rod H is preferably reduced at its rear end and is provided with screw-threads h², (see Fig. 4,) over which screws the piston H², which piston is normally held between the cylinder-head G² and the spring I.

Both ends of the recoil-cylinder are provided with suitable stuffing-boxes G', and the interior of the recoil-cylinder is provided with a tapered groove g⁰ to allow the passage of the fluid from one side of the piston to the other as the gun recoils. The spring I should be normally under tension and strong enough to return the gun to the initial position on counter-recoil. The forward end of the recoil-cylinder is preferably tapered, as at g' 85 and g², to pass freely into the U-shaped projection C⁶ should the parts be out of alignment somewhat, while the rear portion of the cylinder G is provided with a spherical rib g, engaging in the corresponding annular recess 95 b² at the rear end of the U-shaped projection B', fast to the band B, whereby the piston is held and centered in position, while at the same time sufficient freedom of motion of the cylinder about the front bearing of the piston-rod is provided for. By this construction of the recoil-cylinder and connections between it and the rocking slide and gun-mount any accident due to the parts being out of alignment is avoided.

The downward projection B' is provided with a lug or pin b⁰ to which the spring L is secured under tension, by means of which spring the breech is closed automatically after counter-recoil, as will be hereinafter more fully described. This spring L is connected, by means of the turnbuckle L', to the lug or pin n on the hand-lever N, secured to the rock-shaft M, by means of which the breech mechanism is operated. By means of this turnbuckle L' the tension of the spring L may be adjusted as required, which tension should be sufficient to always close the breech after it has been opened, but at the same time not excessive enough to prevent the easy opening of the breech by the hand-lever N when desired, this hand-lever acting against the tension of said spring.

The opening of the breech is normally effected automatically by the mechanism that will hereinafter be described; but it is frequently desirable, especially in drilling, to open the breech by hand, and with the herein-described mechanism this also may be done when desired.

K represents the breech-block, which slides in its chamber in rear of the powder-chamber of the gun. This breech-block chamber in rear of the gun is provided with the ribs

a' , one on each side, inclined at the rear, as at a^2 , in front of the rounded shoulder a , which rib and shoulder are set at a small angle, preferably about three degrees, with a line at right angles to the axis of the bore, so as to wedge the breech-block home when it is raised, to the closed position.

The sides of the breech-block are provided with the straight ribs k and k^3 , with the surfaces k' and k^3 adapted to register with those of the rib a' and incline a^2 , while the rear face of the block is rounded at its outer edges to register with the rounded shoulder a . The top of the breech-block is recessed, as at k^0 , which recess slopes forward and downward, as at k^{00} , so that it will receive the projectile or cartridge-case, and the rim of the latter will be wedged down this incline k^{00} during the first stages of raising the breech-block after the fixed ammunition has been put in the gun.

The rear of the gun terminates in the U-shaped rib A^2 , rounded outward and downward, so as to admit the free passage of the projectile into the bore from the rear when the breech-block is in the open position, as shown in Fig. 11. The front portion of the breech-block is provided with the T-shaped central chamber K' , the wider upper portion of which is partly shut in by the ribs k^4 , against which the cam-faces m' of the cam-head M^2 of the operating-arm M' engage. The operating-arm is rigidly attached to the rock-shaft M . The upper side of the head M^2 is rounded, as at m^2 , and engages the upper wall of the chamber K' . Thus the surfaces m^2 cam the breech-block upward into the closed position, while the cam-surfaces m' cam the breech-block downward toward the open position. The forward portion k^{05} of the cam-face k^5 is concentric with the axis of the rock-shaft M , allowing extra movement of the cam-head M^2 after the block is in the highest position to lock the same. By reference to Fig. 11 it will be seen that the arm M' will act on the breech-block as a short lever-arm when beginning to raise the block, thus starting the block slowly with great power, and that the lever-arm increases with corresponding increase of speed until the block is in nearly the highest position, the final act of wedging the block into the tightly-closed position being effected by the powerful camming effect of the cam M^2 on the cam-surface k^5 , as shown in Fig. 9, while in opening the breech-block the slow but powerful starting effect is secured by the cam-surfaces, and then the block is moved rapidly downward by the lever-arm, supplemented by the weight of the block and the parts moving therewith, until the block is arrested by striking the upper surface of the arm N' near its pivot, as shown in Fig. 11, when the said arm reaches the lower limit of its travel. The position of the rock-shaft normally below and in front of the breech-block, together with the advantages of operation just described, makes it possible to use a short and light operating-

arm, on which the block is supported from beneath, instead of the long heavy arm and binding support most common in the art. Moreover, great ease and convenience of manipulation are secured, and the parts referred to are placed in a position clear of the loading apparatus and of the rim of the cartridge-case and protected against the enemy's projectiles and also against sand, dirt, rain, &c.

The breech-block is provided with a recess for the firing-pin terminating in the pin-hole k^9 , through which the point of the firing-pin is projected when the gun is fired.

The extractors R consist of the vertical plates R' , bent at right angles at R^2 and terminating in the engaging rib R^3 , which are curved, as at r , to engage in front of the rim z of the cartridge-case Z , while the backs of these ribs R' are rounded somewhat, as at r' , to form a pivot for the extractor during the operation of starting the cartridge-case to the rear after the gun has been fired. The lower portion of the extractor is provided with two oppositely-disposed lugs R^4 and R^5 , which project into the curved recess A^4 in the wall of the breech-block chamber and the groove K^6 in the side of the breech-block, respectively. The lug R^5 is flattened, as at R^4 , on the side opposite to the rib R^3 to lock the breech-block in the open position, as will be hereinafter described. The lug R^6 travels in the cam-groove K^5 in the side of the breech-block, which cam-groove has the operating portion k^6 , adapted to move the heel of the extractor forward as the breech is opened and rearward as the breech is closed, and also the large portion k^7 , open to the front, which permits the breech-block to be withdrawn from its seat without being impeded by the lugs of the extractors. Near the upper end of this cam portion k^6 of the groove K^5 the lower wall of this groove terminates in the flat shoulder k^8 , adapted to engage beneath the flat surface r^3 of the lug R^4 when the extractor is in the rearward position and the breech-block is in the open position. Thus as the breech-block is moved down by the rotation of the rock-shaft M the lug R^5 of the extractor is cammed forward in the groove K^5 of the breech-block, while the lug R^4 moves forward in the groove A^4 in the wall of the breech-block chamber. When the breech-block reaches the lower or open position, as indicated in Fig. 11, the lug R^5 will have passed out of the groove k^6 into the recess k^7 , and the plane face r^3 will be above and will engage the shoulder k^8 , thus preventing the breech-block from moving upward until the extractor has been moved forward far enough to release the engagement of the plane surface r^3 and the shoulder k^8 .

The loading of the gun will automatically trip the extractor out of engagement with the shoulder k^8 , because as the cartridge-case is shoved home the rim of the cartridge-case will engage the rib R^3 and will push the extractor forward from the position shown in full lines in Fig. 12 toward that shown in dot-

ted lines in said figure, and the breech-block will then be free to be moved upward in the closed position either by hand or by the automatic attachment that will herein be described.

It will be obvious that the breech may be opened and closed and the extractors operated by means of the hand-lever N; but the breech is preferably opened by means of the automatic attachment that will now be described and closed by means of the spring L.

The automatic breech-opening mechanism includes two perforated arms C⁶, attached to or integral with the rearward-projecting arm C² of the rocking slide, between which arms C⁶ the cam-plate Q is pivoted, as at q⁰. This cam-plate is normally pressed inward by the spring Q² engaging in a recess c⁹ in the web c¹, spanning the upper portion of the arms C⁶. The inward travel of the pivoted cam-plate is limited by the lug q¹, which engages beneath the lower face of the web c¹, while this lug terminates in two arms q⁸, between which the bell-crank lever Q⁸ is pivoted, having the short arm q¹¹, adapted to engage the lug c⁸, and thus by a motion of this bell-crank lever from the position shown in full lines to that shown in dotted lines in Fig. 20 the cam-plate may be swung backward from the engaging position to the position in which it will be out of engagement with the operating mechanism, when all the parts engaged in opening the breech may be operated entirely by hand. Thus the automatic breech-opening mechanism may be thrown into and out of engagement as desired.

The cam-plate Q is provided with a cam Q' and certain inclined faces q to q⁴, which will be hereinafter more fully described.

The rock-shaft M has an arm P, provided with a lug p, which lug engages the cam Q' and opens the breech automatically on counter-recoil. This operation is as follows: The lug p is normally either in front of or in engagement with the inclined face q of the cam-plate Q. As the gun is fired and recoils this lug p moves to the rear with the gun, sliding up the inclined face q and wedging the cam-plate Q outward against the action of the spring Q². As soon as the lug p passes beyond the end q' of the inclined face q of the cam-plate Q, the gun springs inward again to the normal position, (shown in full lines in Fig. 20,) and as the gun moves forward on counter-recoil due to the energy stored up in the spring I the lug p moves down the curved face q² of the cam Q', causing the arm P to revolve the rock-shaft M far enough to open the breech-block. When the lug p has reached the lower part q³ of the cam Q', the breech-block is in the open position and the lug P moves out of engagement with the cam and would slide upward and press the cam-surface q³ until it jumps over the shoulder q⁶ along the rear face q⁴ were it not for the fact that the extractor locks the breech-block in the open position. As soon as the extractor is pressed forward far enough

to release the breech-block, which may be done either by hand or automatically by the insertion of a new cartridge-case, as in loading the gun, the breech-block is released, and the spring L, acting on the lever-arm N, rotates the rock-shaft M, moving the breech-block up to the closed position. At the same time the lug p returns to the initial position relative to the cam-face q. Thus it will be seen that when the gun is fired it recoils and the breech-block is opened on counter-recoil and locked in the open position until the gun is reloaded or until the breech-block is purposely released, when the breech is automatically closed. Moreover, it will be obvious that the operation of the cam Q' takes place wholly on counter-recoil and that this operation is not affected by the distance through which the gun recoils, provided the recoil be sufficient to carry the lug p from one side of the cam Q' to the other side thereof. It will also be evident that the automatic arrangement does not interfere with the operation of the breech mechanism by hand, if desired.

In order to provide adequate rigidity to the rear end of the arm C², near the cam-plate Q, and also to still further prevent the error known as "jump," the breech of the gun may be provided with dovetail guides a², sliding in guideways c² in the arm C² of the rocking slide, as shown in Figs. 10 and 20. Thus the object of the additional rear bearing is principally to increase the leverage of the bearing-surfaces that prevent jump. The short sliding connection between the sleeve B and rocking slide C obviously permits more freedom of motion in a vertical plane than in this construction, where the guide is practically made four times as long. Therefore with the same necessary clearance between sliding surfaces there should be only about one-fourth as much jump possible. Thus the error due to wear, to yielding of the parts on recoil, or to lack of trueness in the sliding contact between the gun and the rocking slide is reduced by increasing the distance apart of the bearing-surfaces between the gun and the rocking slide.

In order to provide for the ready removal of the breech-block from the gun for any purpose, the rock-shaft M is journaled in the hook A', projecting beneath the breech of the gun, which hook is provided with the lips a', projecting laterally therefrom. These lips a' engage beneath corresponding lugs n⁰ and p⁰, projecting inward from the end plate n' and the lower side of the arm P, as shown in Fig. 16, which lugs n⁰ and p⁰ pass out of engagement with the lower face of the lips a' when the breech-block is raised slightly beyond the closed position, but engage the said lips a' when the breech-block is fully or partly closed, and thus if the breech-block is closed and raised slightly beyond the closed position these lugs n⁰ and p⁰ may be swung clear of the lips a', the rock-shaft may be lifted out

of the hooks A¹, and then the breech-block, rock-shaft, &c., may be thrown out of engagement with the gun and removed and a fresh breech-block, rock-shaft, &c., inserted or substitution may be made, as may be desired.

It will be seen that the means for operating the breech-block, whether automatically or by hand, for locking the breech-block in the open position, for operating the extractors, and in general the means for operating the breech mechanism, which have herein been described, are in no sense limited to any specific form of firing mechanism, and it is our purpose to apply any suitable or desired form of firing mechanism to the invention already described. We have shown, however, a preferred form of firing mechanism, in which T represents a sliding trigger-plate mounted in guides beneath the rib c¹⁰ of the sighting-arm C³ and terminating in a trigger t, which trigger may be provided with a suitable guard, (not shown,) if desired. This sliding trigger-plate T is provided near its forward end with a recess, terminating in the lug t', in which recess and the recess c¹³ of the rib c¹⁰ the spring T' is mounted. This spring normally presses forward the plate T, which plate is provided with a lug t'', adapted to engage the arm V' on the shaft V, as shown in Figs. 22 and 25.

The firing mechanism is operated from the shaft V in a manner that will hereinafter be described. The sliding plate T has secured thereto a resilient plate T'', terminating on a hook t'', which hook normally engages the lug c¹², (see Figs. 5, 22, and 24,) secured to or integral with the arm C². When the lug p is raised to the highest position, which takes place only when the breech-block is closed and locked, the last part of its travel during the time the cam M² moves along the face h⁰³ will cause it to press up beneath this resilient plate T'' until the hook t'' is released from engagement with the lug c¹², and thus the plate T'' may be drawn to the rear only when the breech is in the closed and locked position, thus affording an automatic means for preventing the gun from being fired by the firing mechanism when the breech-block is in any but the fully closed and locked position.

The shaft V is pivoted in a chamber a⁰ across the breech of the gun and is provided with the cocking and firing toe V². This toe, when inserted or removed slides in a suitable groove a⁰¹ (see Fig. 12) in the breech of the gun, which groove at its central portion is widened to allow the toe V² to rotate through the desired angle. One end of the shaft V is inclosed by the coil-spring V³, the ends of which spring engage in the recess v' in the arm V' and in a suitable recess in the body of the gun. The spring is normally under tension, tending to rotate the shaft V so as to cause the toe V² to project forward into the vertical groove a⁰² in the path of the arm w' of the cocking-lever W, which is pivoted at w in the breech-block. Thus the toe V²

normally holds the cocking-lever in the cocked position, as shown in Fig. 9, or tends to engage the sear as the breech-block is returned to the closed position, as shown in Fig. 11. As the plate T is drawn to the rear, as in firing the gun, the shoulder t⁰ pulls the toe V² out of engagement with the cocking-lever W and allows the spring-operated firing-pin to fire the gun. After the gun is fired the spring T' will return the sliding plate T to the initial position, while the spring V³ will throw the toe V² forward again, which toe will be pressed backward into its recess a⁰¹ as the arm W' of the cocking-lever W passes in opening the breech-block and will spring forward again to the position shown in Fig. 11 as the breech-block is opened, being then in a suitable position for cocking the firing mechanism.

The firing-pin X is operated by the spring X', bearing against the head x of the firing-pin and also against the bushing X², screwed into the rear of the breech-block. This head x is slotted, as at x', to permit the passage of the head past the pins Y, which pins are mounted in the breech-block, near its forward face, and project slightly into the cavity for the firing-pin. These pins Y may be secured in the breech-block in any convenient way, but are preferably provided with enlarged heads, screw-threaded, as at y, and screwed into the breech-block, as shown in Fig. 11.

The cocking-lever W is in the form of a bell-crank lever, the short arm w' of which engages the cocking and releasing toe V², while the upper and longer arm w² engages in an elongated recess x² in the firing-pin X. The base of the firing-pin is provided with an opening x³ in front of the rear piece x⁴ for cocking by hand, as with a hook or lanyard or in any other convenient way.

The arm w² of the cocking-lever projects also through a slot in the lower side of the bushing X², and the front face of this arm is curved forward slightly, so as to project into the cavity for the firing-pin and to take up the rearward pressure of the spring X' while the firing-pin is in the forward position. Thus in this position the spring X' would press against the arm w² of the cocking-lever instead of against the bushing X² and would cause the sear to press rearward against the firing-pin, removing the point of the firing-pin from the face of the breech-block after the gun had been fired. The inertia of the firing-pin and connected parts would be sufficient to carry the firing-pin forward to the firing position; but as soon as the head x of the firing-pin passes the inner ends of the pins Y the driving effect of the spring X' would be removed from the head of the firing-pin, while about the same time the rearward pressure of the firing-spring X' would be shifted from the bushing X² to the arm w² and the effect of the spring will be changed from that tendency to push the firing-pin forward to a tendency to move the firing-pin backward or in a reverse direction, and thus

the fragile point of the firing-pin will be withdrawn within the inside of the protecting-face of the breech-block before the breech-block can be moved downward. Thus it will be seen that the firing mechanism is automatically protected against premature discharges, and the point of the firing-pin is protected against possible accidents in opening and closing the breech and also against accidentally striking the primer while the cartridge-case is in the gun.

For convenience in transportation, manipulation, &c., we preferably make the sighting-arm C³ detachable from the rearward-projecting arm C² of the rocking slide. For this purpose the arm C³ is provided with wedge-shaped dovetailed ribs c³, engaging beneath the ribs c² of the arm C², while the locking-spring c⁴ is provided with a notch c⁵ and thumb-lug c⁶. The notch c⁵ engages in a suitable catch in the arm C², (see Fig. 23), and thus the ribs c² and c³ and this catch and spring hold the arm C³ in firm engagement with the arm C².

25 When it is desired to detach the arm C³, this may readily be done by pressing on the thumb-lug c⁶ and drawing the arm C³ to the rear.

It will be obvious that various modifications 30 may be made in the herein-described apparatus, which could be used without departing from the spirit of our invention.

Having thus described our invention, what we claim as new, and desire to secure by Letters Patent of the United States, is—

35 1. In a rapid-fire breech-loading gun, the combination with a breech-block, of a spring-constrained arm operating the same, a non-recoiling cam pivoted parallel to the axis of 40 the bore and carried by the gun-mount and engaging said arm, a spring normally pressing said cam toward the gun, and a bell-crank lever for throwing said cam into and out of engagement, substantially as described.

45 2. In a rapid-fire breech-loading gun, the combination with a breech-block, of a spring-constrained arm operating the same, a non-recoiling cam pivoted parallel to the axis of 50 the bore and carried by the gun-mount and engaging said arm in opening the breech on counter-recoil, a spring normally pressing said cam toward the gun, means for throwing said cam into and out of engagement when desired, and means for closing the breech 55 when desired, substantially as described.

3. In a rapid-fire breech-loading gun, the combination with a breech-block, of a spring-constrained arm operating the same, a non-recoiling cam pivoted parallel to the axis of 60 the bore and carried by the gun-mount and engaging said arm in opening the breech on counter-recoil, a spring normally pressing said cam toward the gun, means for throwing said cam into and out of engagement when 65 desired, means for holding the breech-block in the open position, and means for closing

the breech when desired, substantially as described.

4. In a rapid-fire breech-loading gun, the combination of a breech-block, a spring-constrained arm operating the same, a non-recoiling cam pivoted parallel to the axis of the bore and engaging said arm for opening the breech-block by energy of recoil, a spring normally pressing said cam toward the gun, means for throwing said cam into and out of engagement when desired, means for locking the breech-block in the open position, means for releasing the breech-block when desired, and means operated by said spring-constrained arm for closing said breech-block, substantially as described.

5. In a breech-loading gun, the combination with a breech-block of a pivoted yielding cam and spring-controlled arm regulated by said cam and operated by the energy of the recoil of the gun for operating the breech-block, a bell-crank lever for throwing said cam into and out of operation, means for locking the breech-block in the open position, and means for releasing the breech-block when desired, substantially as described.

6. In a breech-loading gun, the combination with a breech-block of a pivoted yielding cam and spring-controlled arm regulated by said cam and operated by the energy of the recoil of the gun for operating the breech-block, a bell-crank lever for throwing said cam into and out of operation, automatic means for locking the breech-block in the open position, and means for releasing the breech-block when desired, substantially as described.

7. In a breech-loading gun, the combination with a sliding breech-block provided with a T-shaped cam-groove in the forward and lower portion thereof for the operating-arm and cam-grooves in the sides for the extractors, a rock-shaft journaled in or on the gun, and provided with a T-shaped operating-arm and cam, means for rotating said rock-shaft to the open and then to the closed position, and extractors having lugs projecting into said side grooves and operated by the motion of said breech-block; substantially as described.

8. In a breech-loading gun, the combination with a sliding breech-block provided with a T-shaped cam-groove in the forward and lower portion thereof for the operating-arm and cam-grooves in the sides for the extractors, a rock-shaft journaled in or on the gun, and provided with T-shaped operating-arm and cam, means operated by stored-up energy of the recoil of the gun for rotating said rock-shaft to the open position, means for automatically closing the breech, and extractors having lugs projecting into side grooves and operated by the motion of said breech-block to withdraw the empty cartridge-case, to hold the breech-block in the open position, and to automatically release the breech-block when the gun is reloaded with fixed ammunition, substantially as described.

9. In a breech-loading gun, the combination with a sliding breech-block provided with a T-shaped cam-groove in the forward and lower portion thereof for the operating-arm and cam-grooves in the sides for the extractors, a rock-shaft journaled in or on the gun, and provided with a T-shaped operating-arm and cam, means operated by the stored-up energy of recoil of the gun for rotating said rock-shaft to the open position, on counter-recoil, means for automatically closing the breech and extractors having lugs projecting into said side grooves and operated by the motion of said breech-block to withdraw the empty cartridge-case and to lock the breech-block in the open position, substantially as described.

10. In a breech-loading gun, the combination with a sliding breech-block provided with a T-shaped cam-groove in the forward and lower portion thereof for the operating-arm and cam-grooves in the sides for the extractors, a rock-shaft journaled in or on the gun, and provided with a T-shaped operating-arm with a cam on said arm, means for rotating said rock-shaft to the open and then to the closed position on counter-recoil, and extractors engaging in said side grooves and operated by the motion of said breech-block to withdraw the empty cartridge-case, to hold the breech-block in the open position, and to automatically release the breech-block when the gun is reloaded with fixed ammunition, substantially as described.

11. In a breech-loading gun, the combination with a sliding breech-block provided with a T-shaped cam-groove in the forward and lower portion thereof for the operating-arm and cam-grooves in the sides for the extractors, a rock-shaft journaled in or on the gun, and provided with a T-shaped operating-arm and cam, means operated by stored-up energy of the recoil of the gun for rotating said rock-shaft to the open and then to the closed position on counter-recoil, and extractors engaging in said side grooves and operated by the motion of said breech-block to withdraw the empty cartridge-case, to hold the breech-block in the open position, and to automatically release the breech-block when the gun is reloaded with fixed ammunition, substantially as described.

12. In a device for automatically opening and closing the breech, the combination with the operating rock-shaft, and automatic means for rotating the same to close the breech, of an arm secured to said rock-shaft, a lug on said arm, and a pivoted cam yieldingly mounted on the rocking slide and engaging said lug on counter-recoil and a bell-crank lever for throwing said cam into and out of engagement with said lug, substantially as described.

13. In a device for opening and closing the breech either by hand or automatically, the combination with the operating rock-shaft,

and automatic means for rotating the same to open and to close the breech, of a hand-lever and an arm both secured to said rock-shaft, a lug on said arm, and a pivoted cam yieldingly mounted on the rocking slide and engaging said lug on counter-recoil and a bell-crank lever for throwing said cam into and out of engagement with said lug, substantially as described.

14. In a device for opening and closing the breech automatically, the combination with the operating-shaft, and automatic means for rotating the same to open and to close the breech, of an arm secured to said rock-shaft, a lug on said arm, and a pivoted cam yieldingly mounted on the rocking slide and engaging said lug on counter-recoil, means for locking the breech-block in the open position, and for releasing same when desired, and a bell-crank lever for throwing said cam into and out of engagement with said lug, substantially as described.

15. In a device for opening and closing the breech either by hand or automatically, the combination with the operating rock-shaft, and automatic means for rotating the same to close the breech, of a hand-lever and an arm secured to said rock-shaft, a lug on said arm, and a pivoted cam yieldingly mounted on the rocking slide and engaging said lug on counter-recoil, means for locking the breech-block in the open position, and for releasing the same when desired, and a bell-crank lever for throwing said cam into and out of engagement with said lug, substantially as described.

16. In a device for opening and closing the breech automatically, the combination with the operating rock-shaft, and automatic means for rotating the same to close the breech, of an arm secured to said rock-shaft, a lug on said arm, and a pivoted cam yieldingly mounted on the rocking slide and engaging said lug on counter-recoil, means for locking the breech-block in the open position, means operated by the insertion of the fixed ammunition for the release of the breech-block, and a bell-crank lever for throwing said cam into and out of engagement with said lug, substantially as described.

17. An improved cartridge-case extractor for use in guns of the character described, comprising a plate curved in front to roll along a face of the gun and thus give a decreasing leverage, and bent at right angles to form an engaging face, with two lugs on the heel of the extractor to engage in grooves in the breech-block and gun respectively, substantially as described.

18. An improved cartridge-case extractor for use in guns of the character described, comprising a flat plate R' curved in front as at R² and bent over at right angles as at R³ to form an engaging face, with two lugs R⁴ and R⁵ on the heel of the extractor to engage in the grooves in the breech-block and gun respectively.

tively, one of said lugs being flattened along one side thereof, substantially as and for the purposes described.

19. An improved cartridge-case extractor for use in guns of the character described, comprising a flat plate R' curved in front as at R² and bent over at right angles as at R³ to form an engaging face R³, with two lugs on the heel of the extractor to engage in grooves in the breech-block and gun respectively, the lug engaging in the breech-block being flattened on the lower or heel side thereof, substantially as and for the purpose described.

20. An improved cartridge-case extractor for use in guns of the character described, comprising a plate bent over at right angles to form an engaging face, with two lugs on the heel of the extractor to engage in grooves in the breech-block and gun respectively, and the front edge of the extractor being curved to engage against a face on the gun and secure a rolling contact and an increasing velocity of ejection, substantially as described.

21. The combination in a breech-loading gun, of a gun-body having a vertical wall transverse to and to rear of the powder-chamber, and a pivot-groove for the extractor, of a sliding breech-block and extractor operating cam-grooves in the walls of said breech-block, with a bearing - shoulder provided in the groove in the breech-block, of a cartridge-case extractor mounted between the gun-walls and the breech-block and having oppositely-disposed lugs or projections projecting into said grooves, the lug or projection engaging in the groove in the breech-block being flattened on one side to engage said bearing shoulder, and the said extractor having a curved front face bearing against the wall of the gun transverse to the powder-chamber and thus providing a continuously-decreasing-leverage arm in ejecting the empty cartridge-case, substantially as described.

22. In a breech-loading gun, the combination with a sliding breech-block and a firing-pin mounted therein, a spring inclosing and normally pressing forward on said pin, a bell-crank cocking-lever or sear also mounted in the breech-block and engaging said firing-pin, a rock-shaft journaled transversely in the gun and provided with a cocking-toe engaging said sear, a spring normally holding said cocking-toe in the engaging position, an arm on said rock-shaft, and means for operating said arm and thus tripping said cocking-toe and releasing the sear and firing-pin, when desired, substantially as described.

23. In a breech-loading gun, the combination with a breech - block, of a firing - pin mounted in said breech-block and provided with a slotted head and an elongated slot near the end opposite said head, pins or lugs projecting from the breech-block in the line of the forward travel of the slotted head and adapted to pass into the slots in the head as the latter nears the end of its forward stroke, a spiral spring normally pressing on the rear

of said head but engaging against said pins when the head passes the same, and a sear projecting into said elongated slot and engaging the rear portion of said spring when the firing-pin nears the limit of its forward travel, substantially as described.

24. In a breech-loading gun, the combination with a breech - block, of a firing - pin mounted in said breech-block and provided with a slotted head and an elongated slot near the end opposite said head, or lugs projecting from the breech-block in the line of the forward travel of the slotted head and adapted to pass into the slots in the head as the latter nears the end of its forward stroke, a spring normally pressing on the rear of said head but engaging against said pins when the head passes the same, and a pivoted lever or sear projecting into said elongated slot and engaging the rear portion of said spring when the firing-pin nears the limit of its forward travel, a cocking-toe engaging said sear, and means for operating said cocking-toe, substantially as described.

25. The firing and safety attachment for use in guns of the character described, comprising a sliding trigger-plate, a trigger on said plate, a spring normally pressing said plate forward, firing mechanism operated by the rearward motion of said plate, a resilient hook connected and normally holding said plate against backward motion, and an arm automatically operated by the breech mechanism for tripping said hook and releasing said plate when the breech is closed, substantially as described.

26. In a rapid-fire gun provided with a lug on the side of the gun-body near the breech, the combination with a trunnion-band provided with a hollow U-shaped downward projection with dovetail ribs projecting from the sides of the trunnion-band, a trunnioned rocking slide provided with guideways for said dovetail ribs, and a rear projection with a guideway therein engaging said lug near the breech and also with a hollow U-shaped downward projection closed at the front, a recoil-cylinder mounted in the U-shaped projection from the trunnion-band and projecting into the U-shaped projection from the rocking slide, a piston in said cylinder, and a piston-rod secured to said rocking slide, substantially as described.

27. In a rapid-fire gun of the character described, a trunnion-band provided with a hollow U-shaped downward projection with dovetail ribs projecting from the sides of the trunnion-band, a trunnioned rocking slide provided with guideways for said dovetail ribs, and also with a hollow U-shaped downward projection closed at the front, a tapering recoil-cylinder mounted in the U-shaped projection from the trunnion-band and projecting into the U-shaped projection from the rocking slide, a piston in said cylinder, and a piston-rod secured to said rocking slide, substantially as described.

28. In a rapid-fire gun of the character de-

scribed, a trunnion-band provided with a hollow U-shaped downward projection with dovetail ribs projecting from the sides of the trunnion-band, a trunnioned rocking slide provided with guideways for said dovetailed ribs, and also with a hollow U-shaped downward projection closed at the front, a tapering recoil-cylinder mounted in a socket-bearing in the U-shaped projection from the trunnion-band and projecting into the U-shaped projection from the rocking slide, a piston in said cylinder, and a piston-rod secured to said rocking slide, substantially as described.

29. In a breech-loading gun with breech mechanism operated by a rock-shaft, a journal-bearing for said rock-shaft, consisting of a hook attached to or integral with the gun and tapered lugs on said hook adapted to engage corresponding lips on the rock-shaft and

removably locking the latter in its bearings, substantially as described.

30. In a breech-loading gun, the combination with a breech-block, a rock-shaft for operating the same, means for turning said rock-shaft, lips on said rock-shaft, a hook on the gun serving as a journal-bearing for said rock-shaft, and lugs on the sides of said hook engaging the lips on the rock-shaft, and removably locking the shaft in its bearings, substantially as described.

In testimony whereof we affix our signatures in presence of two witnesses.
